ATTORNEY.

UNITED STATES PATENT OFFICE

ARTHUR ATWATER KENT, OF ARDMORE, PENNSYLVANIA

VACUUM-TUBE HOLDER

Application filed November 15, 1926. Serial No. 148,334.

My invention relates to holders or terminal blocks for vacuum tubes, such as audions or the like, utilized in radio systems and other relations.

5 My invention resides in a holder or terminal block of the character referred to suited particularly for holding or receiving a vacuum tube from whose base projects conductive terminals or stems adapted for insertion 10 in predetermined relation into a group of perforations, and it is a particular object of my invention to provide a holder or terminal block of a character facilitating passage of the tube terminals into the group of 15 perforations in proper relation and also of a character preventing substantial tipping of the tube with consequent impairment of the conductive paths afforded by the spring contacts engaging said terminals.

20 My invention resides in the structure and features of construction of the character hereinafter described and claimed.

For an illustration of one of the various forms my invention may take, reference is to 25 be had to the accompanying drawing, in which:

Fig. 1 is a vertical sectional view of a holder or terminal block with a vacuum tube positioned thereon, and is taken on the line 30 1—1 of Fig. 2 looking in the direction of the arrows.

Fig. 2 is a horizontal sectional view, partly in plan, taken on the line 2—2 of Fig. 1 and looking in the direction of the arrows.

35 Fig. 3 is a bottom view of the structure shown in Fig. 1 with the tube terminals positioned in conductive relation with their contact members.

Fig. 4 is a plan view of the structure shown 40 in Figs. 1 and 2 with the tube removed.

Fig. 5 is a view corresponding with Fig. 1, but taken on the line 5—5 of Fig. 2, looking in the direction of the arrows.

Fig. 6 is a transverse vertical sectional view taken on the line 6—6 of Fig. 4, looking 45 in the direction of the arrows.

Referring to Figs. 1 and 2, there is illustrated a thermionic device V, as a vacuum tube of the audion type, herein shown as 50 comprising the usual glass envelope secured

to and extending from the base 2. As is well understood in the art, the device V comprises a filament or cathode, a grid or control electrode, and a plate or anode. Extending from the base 2 and suitably secured thereto 55 are the conductive members, prongs, terminals or stems 3 of the aforesaid filament or cathode and the conductive members, prongs or terminals 4 and 5 connected, respectively, to the aforesaid grid and plate. 60

It is well understood in the art that the terminals of the vacuum tube may be passed through perforations or passages in a terminal block into conductive engagement with contact or terminal members carried thereby. 65 To the end that the cathode, control electrode and plate terminals shall always be associated only with the proper contact members, it is customary to so form some or all of the various terminals that they differ peripherally among themselves, and to shape the walls of the various passages receiving the terminals in a similar manner. 70

Examples of this type of construction found in the prior art, while satisfactory in 75 some respects, are unsatisfactory in others, primarily because in the restricted space of an ordinary radio receiving set it is difficult to register the tube terminals with the passages in the terminal block receiving the 80 same. Furthermore, even after the aforesaid terminals have been passed through the proper passages in the terminal block, the vacuum tube may come to rest in a variety of positions, or it may be easily tilted, and as a 85 result, the electrical connections between the vacuum tube terminals and the contact members associated therewith often develop high resistance qualities or prove otherwise unsatisfactory. 90

In accordance with my invention, the terminal block of the prior art is replaced by one that is free of the above named defects. To this end, there is provided a terminal block or holder member 6 of moldable material, as rubber, a phenol condensation product, or the like. The tube holder is of a type which dispenses with the barrel, sleeve or socket structure for receiving the base 2 of the tube. Accordingly the holder member 6 with features 100

of structure described itself mounts or holds the vacuum tube and is devoid of any such barrel, sleeve or socket. As particularly illustrated in Figs. 2, 3 and 4, the cathode terminals 3 depending from base 2 are circular in cross section, of the same diameter, and relatively larger than the diameter of the similar terminals 4 and 5 of the grid and plate. Hence, as illustrated in Fig. 4, there are provided in the member 6 the two passages 7 for the aforesaid cathode terminals 3 and the passages 8 and 9 for the aforesaid grid and plate terminals 4 and 5. In conformity with the shape of terminals 3, 4 and 5, the passages 7, 8 and 9 are circular in cross section, and the diameter of each passage 7 is slightly greater than the diameter of terminal 3, while the diameter of passages 8 and 9 is likewise slightly greater than the diameter 20 of terminals 4 or 5.

In order that the vacuum tube terminals may be introduced without difficulty into the aforesaid passages 7, 8 and 9, there is provided a centering lug or shoulder 10, preferably 25 circular in cross section and having its periphery disposed just within the passages 7, 8 and 9. Preferably, the aforesaid lug 10 is formed integrally with the member 6 during the molding operation, and its outer wall slopes from the passages 7, 8 and 9 as indicated at 10^a, Figs. 5 and 6. Obviously, the vacuum tube terminals may readily be centered around the lug 10, and when so centered the tube may be rotated in either direction to 35 cause its terminals to come into registering relation with the proper passages 7, 8 and 9.

The member 10 serves to guide the tube prongs to their passages particularly by virtue of the periphery of the member 10 whose 40 surface is substantially tangent to the upper or receiving ends of the passages. The prong-guiding surface, substantially tangent to the entry ends of at least some of the prong passages, is that of an integral portion of the holder or plate-like member 6.

Suitably secured to the member 6, as by the rivets 11, is the pair of contact members or terminals 12 and the similar contact members or terminals 13 and 14, each of said contact 50 members being formed of phosphor-bronze or other resilient conducting material.

Each contact member 12, 13 and 14 comprises an angular portion 15, Fig. 1, normally occupying a position in the path of a 55 vacuum tube terminal to be inserted through passages 7, 8 or 9, Fig. 4. Each contact member also comprises a relatively flat portion maintained by rivet 11 in engagement with the under side of the member 6, and an angular portion 16 adapted to have a conductor soldered or otherwise suitably secured thereto. Preferably, as indicated in Fig. 1, there is struck up from each contact member a lug or projection 17 which lies within a recess 18 65 in the member 6 and prevents rotation of each

contact member 12, 13, 14 around its rivet 12.

Depending from the terminal block or member 6 is the member 19, preferably of circular cross section, preferably formed integrally with member 6 during the molding operation, and preferably recessed as indicated at 19^a. As illustrated in Fig. 5, the outer periphery of member 19 should form an extension of the inner wall of each of the 70 passages 7, 8 and 9.

After the vacuum tube terminals have been aligned with the proper passages in the holder member 6 as aforesaid, the tube is thrust downwardly, Figs. 1 and 5, the tube terminals, after passing through the passages 7, 8 and 9, first engaging with the wall of member 19, and the ends thereof during continued descent of the tube engaging the angular portions 15 of contact members 12, 13 and 14, thereby deflecting or thrusting the latter aside. Due to their inherent resiliency, however, each contact member at its angular portion 15 frictionally engages a tube terminal. Ordinarily, when in its final position, each of the tube terminals is slightly spaced from member 19, but, upon slight tipping of the tube, one of said terminals engages member 19 and prevents further tipping. However, any possible tipping movement of the tube and its terminals is slight, and, therefore, contacts 12, 13 and 14 are always maintained in good conductive relation with the respective tube terminals.

In furtherance of this phase of my invention, the face of member 6 adjacent base 2 of tube V may be provided with a plurality of upstanding lugs or shoulders 20, Figs. 2, 4 and 6, one each at least being disposed on each side of the group of perforations. When the tube is finally seated on the aforesaid plate 6, the lower surface of base 2 will either have engaged the shoulders 20 or moved closely adjacent thereto. Accordingly, the tube by its base 2 is supported in at least three regions, namely, by shoulders 10 and 20. Ordinarily, the periphery of a base 2 of a vacuum tube forms a slight dependent rim or flange, and, hence, each of the shoulders 20 should rise from member 6 a distance 95 slightly less than does the shoulder 10.

The structure may be secured to any suitable base, and for this purpose there may be provided one or more holes 21 through which may pass screws or other fastening devices.

Holder structure of the character hereinbefore described is particularly adapted for radio apparatus of the type disclosed in my Letters Patent No. 1,658,562 or No. 1,668,155. Obviously, the structure may be adapted for a single tube, as herein illustrated, or may comprise an elongated shelf or support equipped with a plurality of groups of perforations and associated structure.

If desired, the lugs or shoulders 20 may be disposed on member 6 in such position as

to be informative of the position which the terminals 3, 4 and 5 should take when the same are to be passed into the passages 7, 8 and 9. Or to convey such information, a suitable index or mark, as indicated at 22, may be arranged on the upper or outer surface of member 6. Thus, with mark 22 positioned as indicated on the drawing, the tube terminals 3, or those of greater diameter, should be nearest said mark when all are passed into their respective passages.

What I claim is:

1. A holder for a vacuum tube having stem terminals comprising a plate-like member having a central hub and passages for said terminals extending therethrough normal to its substantially plane side; yielding contact members engaging said terminals when the tube is in seated position, and means out of the plane of said side co-acting with the base of said tube to prevent tilting thereof when in said seated position. 70
2. A holder for a vacuum tube having stem terminals comprising a member having passages for said terminals, yielding contact members engaging said terminals when the tube is seated on said member, and means comprising oppositely spaced lugs extending from the plane of said member and adapted to engage the base of said tube. 80
3. A holder for a vacuum tube having stem terminals comprising a member having passages for said terminals, a centering shoulder extending from the plane of said member and co-acting with some of said terminals to facilitate entry thereof into said passages, and means adapted to engage the base of said tube in a plurality of regions to space the same from said member. 85
4. A holder for a vacuum tube having stem terminals comprising a member having passages for said terminals, a centering shoulder extending from the plane of said member and co-acting with some of said terminals to facilitate entry thereof into said passages, and means comprising oppositely disposed lugs extending from the plane of said member lesser distances than does said shoulder and adapted to space the base of said tube from said member. 90
5. A holder for a vacuum tube having stem terminals, comprising a member having passages for said terminals, said member having on the side opposite said tube a centrally disposed stud-like member around which said terminals are positioned whereby the axis of said tube is maintained perpendicular to the plane of said first member. 95
6. A holder for a vacuum tube having stem terminals, comprising a member having passages for said terminals, a centering shoulder extending from one side of said member to facilitate entry of said terminals into said passages, said member having a central stud-like member disposed on the opposite side 100
7. A holder for a vacuum tube having stem terminals, comprising a plate-like member having passages for said terminals, said member having on the side opposite said tube a centrally disposed stud-like member around which said terminals are positioned whereby the axis of said tube is maintained perpendicular to the plane of said first member, and flat contact springs spaced circumferentially about and biased toward said stud-like member for engaging said tube terminals. 110
8. A holder for a vacuum tube having stem terminals, comprising a member having passages for said terminals, a centering shoulder extending from one side of said member to facilitate entry of said terminals into said passages, said member having a central stud-like member disposed on the opposite side thereof around which said terminals are positioned, and flat contact springs spaced circumferentially about and biased toward said stud-like member for engaging said tube terminals. 115
